(57) **CLAIM**

The ornamental design for a computer display with a graphical user interface, as shown and described.

DESCRIPTION

FIG. 1 is a front view of a computer display with a graphical user interface; and,

FIG. 2 is a front view of a second embodiment thereof. The broken line showings of the computer display, text, oblique lines, and horizontal lines are included for the purpose of illustrating portions of the computer display with a graphical user interface and form no part of the claimed design.
